UNITED STATES PATENT OFFICE.

FREDERICK KLEINSMITH, OF INDIANAPOLIS, INDIANA.

CUSHION ADJUSTER.

Application filed April 7, 1926. Serial No. 100,415.

My said invention relates to a novel adjuster for seat cushions of automobiles or other vehicles by means of which the cushion may be forced into position on its supporting seat and held in such position or maintained in various elevated positions for rendering accessible a tool, battery or other compartment beneath the seat, all as will hereinafter be more fully described and claimed.

Referring to the accompanying drawings which are made a part hereof and on which similar reference characters indicate similar parts,

15 Figure 1 is a side elevation of a seat having a part broken away illustrating the application of my invention,

Figure 2, a similar view illustrating one use of my adjuster,

20 Figure 3, a detailed view of one of the members to which the adjuster is secured,

Figure 4, a perspective of one form of the adjuster,

25 Figure 5, a fragmentary view of a seat riser with a bracket attachment for supporting the free end of the adjuster,

Figure 6, a bottom plan view of a seat with my device applied thereto,

30 Figure 7, a detailed view showing the connection of the adjuster to the frame shown in Figure 6,

Figure 8, a modified form of the invention.

In the drawings reference character 10 indicates an automobile seat having a riser 11 at its front edge, a back 12 and a removable cushion 13. An adjuster is provided for forcing or wedging the cushion into position on its support and for holding the same in such position, said adjuster comprising a rod bar or rod 14 of substantially U-shape, or having side bars 14 and a cross bar 15. The free ends of the U-shaped member are preferably bent outwardly in opposite directions and are adapted to engage in apertures 16 in transversely disposed supporting brackets, or cross bars 17 and 18, formed integral with, or attached to longitudinal members 19 and 20 of the seat frame.

50 As shown in Figure 1 the adjuster is adapted to fit snugly beneath the cushion when the same is in position on the seat and a bracket 21 is secured to the seat riser 11 adjacent its upper edge and serves as a support for the free end of the adjuster 14, permitting the adjuster to either bear against

the rear side of the seat riser, so that the seat may be forced into position, or against the ridge in said bracket for holding the seat in an elevated position to permit access 60 to a tool box, or other compartment. The cross bars 17 are preferably provided with a series of spaced apertures 16 to permit the adjuster to be connected in various positions so that the elevation of the cushion may be 65 varied, or variation in size from continued use or other causes be provided for.

When the cushion is removed from the seat the adjuster may be set in the position shown in Figure 2 to serve as a brace for 70 holding said cushion in a forward position to permit free access to the compartment beneath and avoid the necessity of removing the cushion from the automobile.

Instead of using the brackets 17, the outwardly turned portions of the adjuster may be journaled directly in apertures in the wooden cross bars 18, as shown in Figures 6 and 7. If desired washers 22 may be used for spacing the arms of the adjuster from 80 the cross bars 18.

In the modified construction shown in Figure 8 an adjuster 14 similar to the one used in Figures 6 and 7 may be pivoted directly to the seat riser and is adapted to support the forward portion of the seat cushion and force said cushion rearwardly into position when the same is depressed. The adjuster shown in Figures 1, 2 and 4 has its cross bar in a plane spaced from the plane of the side arms of the adjuster and in Figures 6 and 7 the adjuster has its side arm and cross bar in the same plane. Obviously other shapes of adjusters may be used and they may be operatively connected up in various ways. In applying the cushion to the seat, it is difficult to force the same into proper position. However, with the use of my device the cushion may be easily forced into position by resting the cross bar 15 upon the bracket 21 and pressing on the top of the cushion causing the adjuster to act as a lever, or toggle, in conjunction with the portion of the cushion frame and straighten out and force the 100 cushion into proper position. When it is desired to remove the cushion it is only necessary to elevate the front portion of the same when it may be readily removed as will be readily understood.

110 It will be obvious to those skilled in the art that various changes may be made in my

device without departing from the spirit of the invention and therefore do not limit myself to what is shown in the drawings and described in the specification, but only as indicated in the appended claims.

Having thus fully described my said invention, what I claim as new and desire to secure by Letters Patent, is:

1. The combination with a support and back and seat cushions, of a brace extending transversely beneath said seat cushion, a plurality of openings in said brace, a lever disposed in one of said openings and engaging the forward edge of the support for said cushion said lever having its free end shaped to fit snugly beneath the forward portion of the seat cushion said lever constituting with the rear portion of the brace a toggle whereby the said cushion will be forced rewardly, said support having a plurality of spaced projections for engagement by the lever whereby the edge of the seat may be held in various elevated positions, substantially as set forth.
2. A cushion adjuster comprising in combination with a support and back and seat cushions, a brace extending transversely beneath said seat cushion, a lever pivotally connected with said brace for engaging the forward portion of the support said lever having its free end formed to snugly fit beneath the forward portion of the seat cushion and constituting with the rear portion of the brace a toggle whereby the seat cushion will be forced into position said support having a plurality of spaced projections for engagement by the lever whereby the edge of the seat may be held in various elevated positions, substantially as set forth.
3. The combination with a support and back and seat cushions, of a brace extending transversely beneath said seat cushion, an

opening in said brace, a lever disposed in said opening and engaging the forward edge of the support for said cushion said lever having its free end shaped to fit snugly beneath the forward portion of the seat cushion said lever constituting with the rear portion of the brace a toggle whereby the said cushion will be forced rewardly, said support having means for engagement by the lever whereby the edge of the seat may be held in various elevated positions, substantially as set forth.

4. The combination with a support and back and seat cushions, of a brace extending transversely beneath said seat cushion, a lever connected to said brace and engaging the forward edge of the support for said cushion and constituting with the rear portion of the brace a toggle whereby the said cushion will be forced rearwardly into position, said support having means adapted to be engaged by the lever whereby the edge of the seat may be held in various elevated positions, substantially as set forth.

5. The combination with a support and back and seat cushions, of a seat mounting for said seat cushion, a lever connected to said seat mounting for engaging the forward edge of the support for said cushion, and constituting with the rear portion of the brace a toggle whereby the said cushion will be forced rearwardly into position when the same is depressed, said support having means adapted to be engaged by the lever whereby the edge of the seat may be held in various elevated positions, substantially as set forth.

In witness whereof, I have hereunto set my hand at Indianapolis, Indiana, this 5th day of April, A. D. nineteen hundred and twenty-six.

FREDERICK KLEINSMITH.
